RIDING MOWER

William L. Manofsky, Nashville, Tenn., assignor to The
Murray Ohio Manufacturing Co., Nashville, Tenn.

Filed Feb. 20, 1973, Ser. No. 334,097

Term of patent 14 years

Int. Cl. D15—03

U.S. Cl. D40—1 D

Fig. 3

Fig. 4

Fig. 7

Fig. 8

FIG. 1 is a perspective view of the riding mower taken from the front and one side thereof;

FIG. 2 is a perspective view taken from the side shown in FIG. 1;

FIG. 3 is a front perspective view thereof;

FIG. 4 is a rear perspective view thereof;

FIG. 5 is a perspective view of a modified form of the riding mower taken from the front and one side thereof;

FIG. 6 is a perspective view taken from the side shown in FIG. 5;

FIG. 7 is a front perspective view of the riding mower shown in FIG. 5; and

FIG. 8 is a rear perspective view of the riding mower shown in FIG. 5.

I claim:

The ornamental design for a riding mower, substantially as shown and described.
